UNITED STATES PATENT OFFICE.

CHARLES LIONEL MARCUS, OF NEW YORK, N. Y.

VANITY CASE.

Application filed May 26, 1926. Serial No. 111,676.

This invention relates to vanity cases.

An object of the invention is to provide a vanity case of improved construction having the parts thereof combined so that cosmetics and powder puffs may be compactly fitted therein, and yet permit easy and convenient access thereto.

Another object of the invention is to provide an improved vanity case comprising few parts which shall be exceedingly simple in construction, neat in appearance, and practical and efficient to a high degree.

Other objects of this invention will in part be obvious and in part hereinafter pointed out.

The invention accordingly consists in the features of construction, combination of elements, and arrangement of parts which will be exemplified in the construction herein-after described, and of which the scope of application will be indicated in the following claims.

In the accompanying drawing, in which is shown one of the various possible illustrative embodiments of this invention,

Fig. 1 is a perspective view of a vanity case embodying the invention;

Fig. 2 is a plan view of the vanity case showing the same in open position; and

Figs. 3 and 4 are cross-sectional views taken on lines 3—3 in Fig. 2, and 4—4 in Fig. 1, respectively.

Referring in detail to the drawing, 10 denotes a vanity case embodying the invention which is seen to comprise two substantially identical members, a container or receptacle 11, and a cover 12, these members being joined together by a hinge 13 of any suitable construction. There is also provided a suitable reflecting means, such as mirror 14 which may be made in any well understood manner, and is here seen to comprise a metallic sheet having highly polished reflecting mirror surfaces 14^a and 14^b, said mirror being secured to the hinge 13 and adapted to swing between the container 11 and the cover 12 as shown in Fig. 3. To permit the mirror to swing a substantial distance into the cover 12, it has an offset portion 15 adjacent the hinge the purpose of which will hereinafter more fully appear.

In the form shown in the drawing, the container 11 is formed with a single compartment 16 adapted to hold therein a cake of cosmetic, such as a compact face powder 17, the latter being firmly held by cementing

or other suitable means to the bottom of said compartment 16. Said cosmetic 17 is preferably of such height so as to occupy substantially one-third of the entire space of the vanity case 10. The cover 12 is formed with a compartment 18 which is partitioned off by a guard member 19 into sub-compartments 18^a and 18^b. The sub-compartment 18^a is adapted to retain a cosmetic, such as a rouge cake 20 and the compartment 18^b is of proper shape and size to have a rouge puff 21 fitted therein as shown in Fig. 4. The guard member 19 has face portions 19^b extending about said sub-compartments and serves to shield the interior of the cover 12 so as to prevent dirt, and foreign matter from entering and accumulating about said cosmetic 20 and the rouge puff 21. Said guard 19 is made of any suitable metallic or non-metallic light sheet material, such as aluminium, celluloid, or the like. The guard, rouge cake, and puff are preferably made to occupy substantially one-third the entire space of the vanity case.

The remaining third of the contents of the vanity case between the mirror 14 and the face powder compact 17 is preferably made of sufficient shape and size to accommodate a powder puff 21 as shown in Fig. 4.

In using the invention, the vanity case is opened and the mirror 14 is swung to the position shown in dotted lines in Fig. 3, thereby permitting easy and convenient access to the cosmetics. In closing the vanity case, the mirror is swung into the cover 12 so as to abut the face portions 19^b of the guard member 19, thus providing space between the mirror and the cake 17 wherein the powder puff 22 may be gently compressed as shown in Fig. 4. Closure retaining means of any suitable construction, such as a hasp fastener 23 may be provided for releasably holding the cover 12 to the container 11.

It should be noted that by proportioning and arranging the parts as described above, a relatively thin and compactly fitted vanity case is provided wherein the cosmetics and accessories utilize substantially the entire interior and yet are readily accessible for convenient use, particularly, the arrangement and manner of hinging of the mirror whereby the latter is pressed below the top edges of the cover, permits the contents to be compactly held in the device which may at the same time be easily removed.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A vanity case comprising a container and a cover, said container and cover being substantially identical in shape and size and each adapted to hold a cosmetic, a hinge joining the cover to the container, and a double faced mirror secured to the hinge for swinging movement between the container and cover, said mirror having an offset portion to permit the mirror to be positioned a substantial distance into the cover whereby the available space over the container is increased as and for the purposes described and specified.

2. A vanity case comprising a container and a cover, a hinge joining the cover to the container, a double faced mirror secured to the hinge for swinging movement between the container and cover, said cover having

a partitioning guard member adapted to retain a cosmetic, the face portion of said member being disposed inwardly from the rim portion of said cover, said mirror having an offset portion to permit swinging the mirror into the cover to lie flat against said face portion.

3. A vanity case comprising two members hinged together, said members each having a compartment, reflecting means secured to swing relative to said members and into one of said compartments, a cosmetic in said latter compartment, a partitioning guard member disposed to occupy less than the entire depth of said latter compartment, said reflecting means being adapted to lie flat against said guard member when swung into said latter compartment.

4. A vanity case comprising a container and cover, said container and cover being substantially identical in shape and size, cosmetics fitted to occupy less than the entire depth of the container and the cover, a hinge joining the cover to the container and a relatively thin metallic, double faced mirror secured to the hinge for swinging movement relative to the container and cover, said mirror having an integral offset portion to permit positioning thereof into said cover whereby a space is provided between said mirror and the cosmetic in said container, and a powder puff disposed in said space.

In testimony whereof I affix my signature.

CHARLES LIONEL MARCUS.
